(57) **CLAIM**

The ornamental design of a distributed control system module-mounting base, substantially as shown and described.

DESCRIPTION

FIG. 1 is a front and left side perspective view of a distributed control system module-mounting base in accordance with the present invention;

FIG. 2 is a front and right side perspective view of the distributed control system module-mounting base in FIG. 1; FIG. 3 is a front elevation view thereof;

FIG. 4 is a top plan view thereof;

FIG. 5 is a right side elevation view thereof;

FIG. 6 is a left side elevation view thereof;

FIG. 7 is a rear elevation view thereof;

FIG. 8 is a bottom plan view thereof;

FIG. 9 is a front and left side perspective view of another embodiment of a distributed control system module-mounting base in accordance with the present invention;

FIG. 10 is a front and right side perspective view of the distributed control system module-mounting base in FIG. 9; FIG. 11 is a front elevation view thereof;

FIG. 12 is a top plan view thereof;

FIG. 13 is a right side elevation view thereof;

FIG. 14 is a left side elevation view thereof;

FIG. 15 is a rear elevation view thereof; and,

FIG. 16 is a bottom plan view thereof.
